SHIP HULL AND METHOD OF CONSTRUCT-
ING IT

George Chauncey Parsons, New York, N. Y.

Application June 23, 1938, Serial No. 215,325

9 Claims. (Cl. 114—79)

This invention relates to hulls for ships, flying boats, etc., and methods of constructing the same.

The principal object of the invention is to provide a simple, cheap, metal hull construction, suitable for small ships, say 25 to 60 feet in length. Metal hulled ships have numerous advantages over wooden. They may be welded so that there is no possibility of water seeping in through the seams. They are immune to the action of marine borers, like the teredo. They have great strength, and, if kept properly painted, almost indefinite life. The chief obstacle to the production of small metal hulled boats has been their cost.

For ships under 60 feet, the cost of rolling or otherwise deforming initially flat plates to give them the desired curvature, both transversely and longitudinally of the ship, is prohibitively expensive.

According to the present invention, therefore, the hull is made angular in section. The simplest angular hull cross-section which is practicable is one having a V-bottom with a pair of straight transverse sections from each side of the keel to each chine and a second pair of straight transverse sections at an angle to the first sections and extending from each chine to the corresponding gunwale. The four sections of sheathing can each be formed of a long single curved plate.

It will be understood, however, that where reference is made to a single sheathing plate or section the term is meant to include any flat sheet composed of a plurality of sections welded or riveted together so that, geometrically speaking, it assumes when flexed to hull form the curved forms characteristic of a unitary sheet of metal. In practice it is rarely possible to secure sheets of metal of sufficient length to form one entire sheathing section so that usually it is necessary to splice two or more plates together.

The above hull form requires five longitudinal frames, viz.: two gunwales, a keel and two frames at the chines. The four sheathing sections are secured at their margins to these five frames, usually, but not necessarily, by welding. Except in the case of small boats or where the sheathing is exceptionally strong and heavy it is usually necessary, or at least highly desirable, to have a number of intermediate longitudinal frames to support each sheathing section between its welded margins. Similarly, it is usually necessary to use ribs, especially where such intermediate frames are used, as in that case such frames have to be supported by ribs.

The invention is also applicable to hull forms

in which there are seven or more longitudinal frames, but the form having only five is preferred as it meets all ordinary requirements for hull design and is simpler and cheaper to construct.

The difficulties heretofore experienced in making metal-hulled boats of angular cross-section have been due to a lack of appreciation of the geometrical principles involved in producing a hull curved fore and aft from flat plates by merely flexing them to hull form.

There are two cases to consider: first, that in which the transverse sections taken at intervals from stem to stern through any one sheathing plate are all at the same angle to the vertical; second, that in which the angles of such sections change. The first case is ordinarily used only for certain parts of the hull, such as the deck or certain parts of the hull proper. Its constructional principle will not give a satisfactory hull form if used throughout. It is almost universal practice to form the hull so that in the topsides such sections are more nearly vertical amidships than they are near the bow and stern. For the bottom sections those nearest the bow are nearer the vertical than those further aft, the sections progressively approaching the horizontal from stem to stern. However, as it is possible, though not desirable, to form a part of both the topside plates and the bottom plates with sections of constant angle, the geometrical principles involved in the first case should be considered. In that case, the sheathing plate or one longitudinal part of it, is bent in one plane only, so that each transverse section is perfectly straight, as well as being parallel to every other section. If, then, the parts of the ribs opposite each sheathing plate or such part thereof are straight, the plate can be made to contact with the corresponding parts of each rib throughout its length, without curving the outer edges of the rib sections. This is due to the fact that the sheathing can be bent to form without bending the plates in any other plane, i. e., without twisting the ends relatively to the middle and so forth.

In the second case, the fact that the transverse sections through each sheathing plate, either throughout the length of the ship or for a considerable part thereof, make different angles to the vertical means that the sheathing plates are not only bent longitudinally, but also have their ends twisted relatively to their middle section. The result of such twisting is that the sheathing plates are bowed outwardly transversely so that they cannot contact with a straight rib section except at its ends and edges. This transverse

bowing or curving of the sheathing greatly increases its strength and stiffness so that in some cases it is possible to dispense with the ribs and/or intermediate longitudinal frames. The transverse bowing of the plates also greatly improves the looks of the boat as it avoids any dead-flat appearance on the hull sides and/or bottom.

Heretofore in making small boat hulls of angular form it has been customary to use ribs 10 and to force the sheathing plates inwardly to make them conform to the straight edges of the rib sections. The result on the hull appearance was disastrous. According to the present invention, instead of bringing the sheathing in to fit 15 the framing, the latter is either actually or in effect moved outwardly to fit the natural transverse curves of the sheathing. Usually it is only the intermediate longitudinal frames which are moved outwardly so that the sheathing contacts 20 with the ribs only along the gunwale, chine and keel. It is not necessary that the ribs contact at those points, even. Whether the sheathing plates contact with the ribs throughout or are wholly or in part spaced away therefrom, so that 25 the plates contact only with the main and intermediate longitudinal frames, the sheathing plates have the same transverse curvature.

It is desirable to space the sheathing away 30 from the ribs, as otherwise, if the sheathing is thin and the ship scrapes along the side of a dock or the like, the sheathing is dented inwards up to each rib so that the position of each rib becomes very apparent.

It is not possible, geometrically speaking, to 35 make the deck of a single flat sheet and give it both sheer and camber. Using two plates abutting each other along the center line of the boat at an angle of 170° to 175°, both sheer and camber can be given. With such a construction the transverse sections of each half of the deck from stem to stern all have the same angle to the horizontal.

Two suitable forms of construction are illustrated, by way of example, in the accompanying 45 drawings, wherein:—

Fig. 1 is a side elevation of a hull constructed in accordance with the present invention, the cabin trunk, keel and rudder being shown in dotted lines;

Fig. 2 is a bottom plan view of the same before the fin, keel and rudder have been attached;

Fig. 3 shows the port side of the hull in front elevation and the starboard side in midship section;

Fig. 4 is a section on an enlarged scale of the line 4—4 of Fig. 1;

Fig. 5 is a detail view showing the relationship between the ribs and the intermediate longitudinal frames;

Fig. 6 is a detail view showing the manner in which the keel is connected to the stem;

Fig. 7 is a midship section through an alternative form of construction; and

Fig. 8 shows a section of the same alternative construction taken near the bow.

As shown in Figs. 1 to 6 inclusive, the hull comprises four metal sheathing plates 10, 11 supported by metal framing including ribs 12, 70 longitudinal tubular frames 13, intermediate frames 14, gunwales 15, keel 16, stem 17 and transom 18. Below the metal hull is a built-up wooden keel 19, containing the usual cast iron or lead ballast, all secured to the keel 75 16 by vertical bolts, not shown.

The keel is of channel form and extends from the stem to the transom. It is bent to the desired curvature before it is placed in position. The stem is a flat strip of steel curved to shape. The forward end of the channel keel has a V-shaped slot cut therein, into which the lower end of the stem is inserted. Then the two halves of the end of the keel are forced inwardly against the sides of the stem and solidly welded thereto.

The ribs may be formed, as shown, of straight flat strips butt-welded together at the chine line 20 and also to the gunwales and keel. The upper ends of the ribs are connected together or to the walls of the cabin trunk by deck beams 25. On these beams is laid the deck, which may be 10 of wood or more conveniently of metal plates 26 supported by the beams, either directly or indirectly by means of carlines 27. Where metal plates are used, as shown, the deck beams are 15 made in two parts welded together along the center line of the boat at an angle of 170° to 20 175° to give the desired camber as above explained. If desired, the carlines may be forced upwards against the deck plates by wedges, in the 25 same manner as the intermediate longitudinal hull frames 14.

The cabin-trunk 21 may be constructed in a variety of ways. One method is shown and described in connection with Figs. 7 and 8 showing an alternative form of hull construction.

In the hull construction illustrated, there are ten ribs and the angles which the various rib sections make with respect to the vertical change from stem to stern, as shown more particularly in Fig. 3. The result is that the sheathing plates 35 are bowed outwardly, especially near the bow, as indicated in Fig. 4. Also, the bowing is greater in the bottom plates than in the top side plates, as there is more change in angle in the bottom sheathing plates than in the top side 40 sheathing plates.

While the ribs could be cut to fit the bowed form of the sheathing plates, it is easier to mount the intermediate longitudinal frames on the ribs so that in constructing the hull such frames can 45 be pushed outwards to meet the sheathing. This system of construction has the further advantage that, by forcing out the intermediate frames after the sheathing has been welded to the main longitudinal frames, the sheathing can be 50 stretched tight under tension. For these reasons the intermediate longitudinal frames are initially 55 slidably mounted in slots in the ribs, so that by driving wedges 29 into the slots behind the frames they may be forced outwardly against the sheathing plates. When that has been done, the longitudinal frames 14 may be welded in fixed position in the slots in the ribs.

In building the boat the first step is to build up the wooden keel 19, with its attaching bolts 60 extending from its upper edge. The next step is to weld together the keel and stem, as previously explained, drill or cut holes in the keel for the attaching bolts, propeller shaft and rudder head tubes. After the keel 16 has been attached to the 65 wooden keel 19, the ribs are attached. Each pair of rib sections is butt-welded together and then their lower ends are welded to the keel 16 in proper spaced relation and with their upper ends in position for subsequent attachment of the 70 gunwales. The gunwales are then bent to form both horizontally to fit the curvature of the ship's side and vertically in accordance with the sheer of the deck. The gunwales are then welded to the stem and tops of the ribs. The transom is 75

then welded to the gunwales and keel. Next, the tubular longitudinal frames 13 are bent to shape and welded to the stem, transom and tops of the ribs. The deck beams are then welded to the under side of the gunwales and the cabin trunk framing is welded to the deck beams. This completes the framing except for the intermediate longitudinal hull frames 14 and the deck carlines 21. The frames 14 are placed in position in the 10 slots in the forward ribs and then welded to the stem. They are next sprung into hull form, bringing them into engagement first with the slots in the ribs in the midship section, then with those aft and finally with the slots in the transom. 15 They are then held in that position in such a way that they are free to move longitudinally in the slots as well as laterally outwards when the time comes to force them outwardly against the sheathing.

20 The next step is to apply the hull sheathing. The forward ends of the sheathing plates 10 are welded to the stem and then fixed into contact along their margins with the tubular frames 13 and gunwales 15. They are then welded along such 25 margins to the frames 13 and gunwales 15 and finally to the transom 18. The sheathing plates 11 are in similar way welded to the stem 17, tubular frames 13, keel 16 and transom 18. As the sheathing plates are lap- or butt-welded to the 30 gunwales, it may be desirable to cover the joint by a wooden strip 28. Next, the wedges 29 are driven in behind the frames 14 until the latter not only contact with the sheathing plates but also force them outwards under tension to give them 35 a smooth evenly curved form from stem to stern. What that is accomplished the wedges are welded to the ribs and to the longitudinal frames 14. The frames 14 may then be welded to the transom. The ends of the sheathing plates 10, 11, 40 frames 13, 14 and keel 16, which project beyond the transom, are cut off and ground flush with the latter.

In the construction shown in Figs. 7 and 8, the ribs 30 are bent to form instead of being 45 formed of straight sections butt-welded together. The greater number of the ribs are made of a single piece of metal from gunwale to gunwale. However, those ribs in the bow which contact with the stem are, to advantage, made in two pieces, 50 so that their lower ends can be welded to the sides of the stem, instead of its top only. Gusset plates 31 may also be used, as shown, to secure greater rigidity adjacent the stem and keel and to serve as floor timbers.

55 In this case the ribs are of angle form with one web projecting outwardly toward the sheathing plates, while the other web extends substantially parallel to such plates. This rib section is much stronger per pound than the flat section of Figs. 1 to 6, and hence the ribs may be made lighter 60 without sacrificing strength.

Another feature of this alternative form of construction is the use of semi-cylindrical longitudinal frames 32 at the chines, which also reduces the hull weight somewhat.

65 The deck beams 33 are also of angle form, but in this case the laterally extending webs are on the outside and the deck plates 34 are welded directly thereto. This is possible because the 70 deck plates are not curved transversely.

75 The cabin trunk framing comprises a plurality of angle bars bent into shallow inverted U-shaped frames 35, each having the same contour although the height of their sides varies somewhat due to the sheer of the deck. As the frames all

have the same contour, the plate 36 forming the roof of the cabin trunk can be bent around and welded to all of the frames. The bottoms of the frames 35 may be connected to the inner ends of the deck beams by angle bar carlines 37 welded 5 to both the frames and deck beams.

What is claimed is:

1. A metallic hull for a ship comprising a frame having a keel, a stem, a transom and a plurality of ribs disposed at different angles 10 to a vertical plane passing through said keel, a plurality of hull-length metallic sheets fixed at their ends to the stem and transom and fixed at their edges to the frame, said sheets being flexed and twisted over the ribs into longitudinal 15 and transverse curvatures conforming substantially to the angular inclination of said ribs, whereby said sheets are tensioned and maintained in said transverse and longitudinal curvatures without buckling.

20 2. A metallic hull for a ship comprising a frame having a keel, a stem, a stern element and a plurality of spaced ribs disposed at different angles to a vertical plane passing through said keel, a plurality of hull-length metallic sheets 25 fixed at their ends to said stem and to said stern element and connected at their adjacent edges in watertight relationship, said sheets being flexed and twisted over said ribs into longitudinal and transverse curvatures conforming sub- 30 stantially to the angular inclination of said ribs, whereby said sheets are tensioned and maintained transversely and longitudinally curved.

3. A method of constructing metallic hulls for ships of angular cross-section comprising welding longitudinal frames to the angles of the ribs, placing intermediate longitudinal frames in slots along the outer margins of the ribs, welding the longitudinal edges of the metal sheathing plates 35 to the first mentioned frames and then bowing 40 said plates outwardly under tension by forcing the intermediate longitudinal frames outwardly against the inner faces of the said plates.

4. A method of constructing metallic hulls for ships of angular cross-section comprising welding longitudinal frames to the angles of the ribs, placing intermediate longitudinal frames in slots along the outer margins of the ribs, welding the longitudinal edges of the metal sheathing plates 45 to the first mentioned frames and then bowing 50 said plates outwardly under tension by driving wedges between the bottom of the slots in the ribs and the intermediate longitudinal frames.

5. A method of constructing metallic hulls as in claim 4, in which the intermediate longitudinal frames are first welded to the stem, then sprung into the curved form of the hull to bring them into engagement with the slots in the ribs, next forced out against the sheathing plates by 55 wedges and finally welded to both ribs and 60 wedges.

6. A method of constructing metallic hulls for boats comprising assembling a frame for said hull, flexing elongated metallic sheets longitudinally and twisting said sheets over said frame 65 to stress and curve them longitudinally and transversely into hull form, and adjusting said frame to conform to the transverse and longitudinal curvatures of the sheets.

7. A method of constructing metallic hulls for 70 ships comprising fixing ribs to a keel, mounting movable reinforcing members in said ribs, flexing elongated sheathing plates over said ribs and connecting them at their adjacent edges and moving said reinforcing members outwardly into 75

engagement with said sheathing to maintain them flexed and under tension.

8. A method of constructing metallic hulls for ships comprising fixing a plurality of ribs to a 5 keel to form a frame, at least some of said ribs having portions inclined at different angles than other ribs to a vertical plane passing through said keel, mounting movable reinforcing members on said ribs, flexing and twisting a plurality 10 of elongated metallic sheets over said ribs to form a sheathing having portions stressed and curved longitudinally and transversely, connecting said sheets in water-tight relationship and adjusting said reinforcing members to engage 15 the inner surfaces of said sheets.

9. A metal hull ship of the type having an angular cross-section, comprising metal framing including metal ribs, stem and transom, longitudu-

dinal frames welded to the stem and transom and also to the ribs at the corners and ends thereof, and intermediate longitudinal frames also welded to the ribs, stem and transom, said ribs having slots along their outer margin to receive said intermediate longitudinal frames, and metal sheathing plates the length of the ship welded at their ends to the stem and transom and also welded along their longitudinal edges to the first mentioned longitudinal frames, the intermediate frames projecting somewhat beyond the line of contact of the plates with the corner frames to give the framing a transverse curvature corresponding to the natural transverse curvature of the sheathing sections when bent to 15 hull form. 5 10 15
